UNITED STATES PATENT OFFICE.

WILLIAM FREDERICH HOFMANN, OF BROOKLYN, NEW YORK, ASSIGNOR TO H. L. JUDD CO., OF NEW YORK, N. Y., A CORPORATION OF DELAWARE.

DESIGN FOR A CURTAIN-POLE END.

Application filed March 29, 1927. Serial No. 21,391. Term of patent 3½ years.

To all whom it may concern:

Be it known that I, **WILLIAM F. HOFMANN**, a citizen of the United States, and a resident of New York, borough of Brooklyn, in the county of Kings and State of New York, have invented a new, original, and ornamental Design for a Curtain-Pole End, of which the following is a specification, reference be-

ing had to the accompanying drawing, forming part thereof.

The figure is a perspective view of a curtain pole end embodying my new design.

I claim:

The ornamental design for a curtain pole end, as shown.

WILLIAM FREDERICH HOFMANN.
